LADY'S DETACHABLE HANDLE BRUSH

Morris Ackerman, Brooklyn, N. Y.

Application January 31, 1948, Serial No. 144,189

Term of patent 3½ years

(Cl. D86—10)

To all whom it may concern:

Be it known that I, Morris Ackerman, a citizen of the United States, residing at Brooklyn, county of Kings, and State of New York, have invented a new, original, and ornamental Design for a Lady's Detachable Handle Brush, of which the following is a specification, reference being had to the accompanying drawing, forming a part thereof.

I claim:

The ornamental design for a Lady's detachable handle brush, as shown.

MORRIS ACKERMAN.
